CONTROL OF UNDESIRABLE VEGETATION
Edward J. Soboczenski, Chadd's Ford, Pa., assignor to
E. I. du Pont de Nemours and Company, Wilmington,
Del., a corporation of Delaware
No Drawing. Filed Oct. 22, 1962, Ser. No. 232,311
9 Claims. (Cl. 71—2.5)

This application is a continuation-in-part of copending application Serial No. 89,674, filed February 16, 1961, 10 and of application Serial No. 12,958, filed March 7, 1960, both now abandoned.

SCOPE

This invention relates to 3-substituted-5,6-alkylene 15 uracils and to compositions and methods employing these compounds as herbicides.

More particularly, this invention is directed to the herbicidal use of compounds of the formula

(1)

where:

R is alkyl of 1 through 10 carbon atoms, substituted alkyl of 1 through 10 carbon atoms, aryl of 6 through 14 carbon atoms, substituted aryl of 6 through 14 carbon atoms, aralkyl of 7 through 15 carbon atoms, substituted aralkyl of 7 through 15 carbon atoms, alkenyl of 3 through 10 carbon atoms, alkynyl of 3 through 10 carbon atoms, cycloalkyl of 3 through 12 carbon atoms, cycloalkenyl of 4 through 12 carbon atoms, cycloalkyl alkyl of 4 through 13 carbon atoms, cycloalkenyl alkyl of 5 through 13 carbon atoms, (substituted cycloalkyl)alkyl of 5 through 14 carbon atoms, (substituted cycloalkenyl)alkyl of 5 through 14 carbon atoms, or cyano;

X is oxygen or sulfur; and

n is 3, 4, or 5.

The salts of these compounds can also be used according to this invention. By "salts" are meant those compounds formed with such cations as sodium, potassium, lithium, calcium, magnesium, barium, strontium, iron, manganese and quaternary ammonium.

The uracils of Formula 1 also form novel 1:1 addition compounds with excesses of certain nitrogenous bases. The exact structure of these compounds is not known. Although the compounds are, generally speaking, poorly soluble in water, they are, according to the best available information, believed to be essentially salt-like in structure. They will be symbolized by the following formula, with the understanding that it is representative only, and is not intended to illustrate actual structure:

(2)

2

where:

R is defined as in Formula 1,
n is 3, 4, or 5, and
5 NB is a nitrogenous base having an ionization constant K_b of $\geq 10^{-9}$ in water.
Suitable nitrogenous bases are substituted, unsubstituted, cyclic and acyclic

Amines,
Amidines, and
Guanidines

The amines can be primary, secondary or tertiary amines, polyamines, arylamines, or heterocyclic amines. Illustrative of such amines are:

20 Ethanolamine
Dodecylamine
Ethylenediamine
Hexamethylenediamine
Cocoamidine
Tallowdiamine
Hexamethyleneimine
Cyclohexylamine
Methoxypropylamine
Methylamine
Dimethylamine
Trimethylamine
Ethylamine
Propylamine
Butylamine
Octylamine
Pyridine
Piperidine
Tetramethylguanidine
35 Acetamidine
Benzylamine
Diethylenediamine
2-aminobutanol-1
2-aminoctanol-1
Sec.-butylamine
2-amino-2-methyl-1,3 propanediol
Trimethylenediamine

45 Some of the uracils of Formula 1 also form water stable, novel complexes with phenol and substituted phenols. These complexes have the formula

where:

R is as defined in Formula 1,
Z is hydrogen, chlorine, nitro, alkyl of 1 through 3 carbon atoms, bromine or —OR₄ (where R₄ is alkyl of 1 through 3 carbon atoms),
Y is chlorine or alkyl of 1 through 3 carbon atoms,
m is a number 1 through 5,
n is 3, 4 or 5, and
65 p is 1/2, 1 or 2.

These complexes are also herbicidal, and in this respect, have some advantages over the uracils per se, viz., higher solubility in oils and solvents. They are formulated into herbicidal compositions in the same way as are the uracils themselves.

This invention is also directed to novel uracils, within the scope of Formula 1. These uracils are of the formula

where

R is substituted or unsubstituted cycloalkyl radical containing 3 through 10 carbon atoms, a substituted or unsubstituted cycloalkenyl radical containing 4 through 16 carbon atoms, or a

radical, where

R₁ is methyl or ethyl,

R₂ is an alkyl radical containing 1 through 5 carbon atoms, and

R₃ is hydrogen or methyl, and

n is 3, 4 or 5.

To be included in this formula, as defined for Formula 1, are the salts of these compounds.

In Formulae 1 to 4 the term "substituted alkyl" is intended to include such radicals as

Bromoalkyl of 1 through 10 carbon atoms,
Chloroalkyl of 1 through 10 carbon atoms,
Hydroxyalkyl of 1 through 10 carbon atoms,
Alkoxyalkyl of 2 through 12 carbon atoms,
Alkoxy carbonyl alkyl of 3 through 12 carbon atoms,
Dialkyl amino alkyl of 3 through 12 carbon atoms, and
Cyanoalkyl of 2 through 10 carbon atoms.

Similarly, the terms "aryl" and "substituted aryl" embrace radicals such as

Phenyl,
Naphthyl,
o-Biphenyl,
Pyridyl,
Chlorophenyl,
Bromophenyl,
Alkoxyphenyl,
Dichlorophenyl,
Dibromophenyl,
Fluorophenyl,
Trichlorophenyl,
Alkylphenyl of 7 through 11 carbon atoms,
Dialkylphenyl of 8 through 12 carbon atoms,
Chloroalkylphenyl of 7 through 10 carbon atoms,
Nitrochlorophenyl,
Nitrophenyl,
Dichloronitrophenyl,
Chloroalkoxyphenyl of 7 through 11 carbon atoms,
Trifluoromethylphenyl,
Alkylnaphthyl of 11 through 16 carbon atoms,
Chloronaphthyl,
Tetrahydronaphthyl, and
Indenyl.

The terms "aralkyl" and "substituted aralkyl" are intended to include such radicals as

Furfuryl,
Benzyl,

5 Phenylalkyl of 8 through 11 carbon atoms (total),
Chlorobenzyl,
Dichlorobenzyl,
Alkylbenzyl of 8 through 11 carbon atoms (total),
Dialkylbenzyl of 9 through 13 carbon atoms (total),
10 Nitrobenzyl,
Alkoxybenzyl of 8 through 11 carbon atoms (total), and
Naphthylmethyl.

15 The terms "cycloalkyl," "cycloalkenyl," "cycloalkyl alkyl," and "cycloalkenyl alkyl" will include

Cyclopropyl,
Cyclohexyl,
Cyclohexenyl,
20 Cyclohexylalkyl,
Cyclohexenylalkyl,
Cyclopentyl,
Cyclopentenyl,
Cyclopentylalkyl,
25 Cyclopentenylalkyl,
Norbornyl,
Norbornenyl,
Norbornenylalkyl,
Bicyclo(2,2,2)octyl,

30 Bicyclo(2,2,2)octenyl,
Bicyclo(2,2,2)octylalkyl,
Bicyclo(2,2,2)octenylalkyl,
Cyclopropyl,
Cyclobutyl,

35 Cyclobutylalkyl,
Cyclobutenyl,
Cyclobutenylalkyl,
Hexahydroindanyl,
Tetrahydroindanyl,

40 Hexahydroindenyl,
Hexahydroindenyl alkyl,
Tetrahydroindanyl alkyl,
Hexahydroindanyl alkyl,
Hexahydro-4,7-methanoindenyl,
45 Tetrahydro-4,7-methanoindanyl,
Hexahydro-4,7-methanoindanyl,
Hexahydro-4,7-methanoindanyl alkyl,
Tetrahydro-4,7-methanoindanyl alkyl,
Hexahydro-4,7-methanoindanyl alkyl,

50 Decahydronaphthyl,
Decahydronaphthyl alkyl,
Decahydronaphthyl alkyl,
Tetrahydronaphthyl,
Tetrahydronaphthyl alkyl,

55 Decahydro-1,4-methanonaphthyl,
Decahydro-1,4-methanonaphthyl alkyl,
Octahydro-1,4-methanonaphthyl,
Octahydro-1,4-methanonaphthyl alkyl,
Decahydro-1,4-5,8-dimethanonaphthyl,

60 Decahydro-1,4-5,8-dimethanonaphthyl alkyl,
Octahydro-1,4-5,8-dimethanonaphthyl, and
Octahydro-1,4-5,8-dimethanonaphthyl alkyl.

These cyclic substituents can be further substituted with alkyl groups containing 1 through 4 carbon atoms, methoxy, chlorine and bromine.

UTILITY

70 The uracils of Formulae 1 through 4 represent a new class of herbicides offering farmers and property owners a new and effective method for the control of undesirable vegetation.

75 Certain of these uracils exhibit selective action in crops. By properly selecting a uracil of the invention and a rate

and time of application, weeds growing in fields of such economic crops as corn, cotton, asparagus, sugar beets, red beets, mangels, spinach, potatoes, peanuts and pineapple can be controlled. This selective activity is described in more detail in the examples which follow.

These compounds are also useful for general weed control on industrial sites, railroad rights-of-way, and areas adjacent to croplands.

The concentrations at which the compounds of this invention are to be used will vary according to the result desired, the type of vegetation, the formulation used, the mode of application, weather conditions, foliage density, and other similar factors. Since so many factors play a role, it is not possible to indicate a concentration suitable for all situations. Generally, when they are used for pre-emergence treatment in crops, these uracils are used at concentrations of at least about 0.5 pound of active ingredient per acre. Concentrations of from 0.5 to 3 pounds per acre are preferred.

When used in non-crop applications, the uracils are used at concentrations of from 10 to 30 pounds of active ingredient per acre. The optimum concentrations to be used in any particular application will be readily apparent to one skilled in the art.

The preferred compounds for use according to this invention are the compounds of Formula 1 where

R is an alkyl or alkenyl radical containing 3 through 6 carbon atoms, phenyl, substituted phenyl, cycloalkyl radical of 3 through 10 carbon atoms or cycloalkenyl radical of 4 through 10 carbon atoms,

X is oxygen, and
n is 3, 4, or 5,

and their sodium, and potassium salts, nitrogenous base addition compounds and phenol complexes.

PREPARATION OF COMPOUNDS

The substituted uracils of Formula 1 can be prepared according to the following equations:

In Equations 5 and 6 R, X, and n have the same meaning as in Formula 1; R₅ is an alkyl radical of 1-6 carbon atoms, H⁺ is an acid, and B⁻ is a base.

The reaction sequence consists of two steps: first, the acid catalyzed condensation of a 1-substituted urea or thiourea with an alkyl 2-cycloalkanone-1-carboxylate to give the ureido intermediate; and, second, the alkaline ring closure of this intermediate to the salt of the uracil product, followed by treatment with acid to liberate the free uracil.

The first step, illustrated by Equation 5, is best carried out by dissolving or suspending the 1-substituted urea or thiourea in a solvent such as xylene, benzene or a

5 mixture of benzene and dioxane, and heating to reflux. To this solution is then added a mixture of the acid catalyst in slight excess of the alkyl 2-cycloalkanone-1-carboxylate. Suitable acid catalysts are phosphoric, polyphosphoric, formic, chloroacetic, or Lewis acids such as BF₃ and AlCl₃. The mixture is stirred and heated to reflux until the water, split out during the reaction and collected in a suitable apparatus, ceases to be given off. The clear solution is decanted or filtered and then concentrated to give the intermediate ureido derivative.

10 In the second step, illustrated by Equation 6 the ureido intermediate is dissolved in alcohol containing a slight excess of base, preferably an alkali metal alkoxide or hydroxide, and the solution is refluxed for a short time. This step effects the ring closure. The salt of the uracil is obtained by concentrating this solution to dryness. The free uracil is prepared by acidifying an aqueous solution of the salt, and then isolating the solid.

15 These compound can also be prepared as described in Archives of Biochem. and Biophys., 83, 141 (1959).

The salt of the compounds of Formula 1 are prepared by conventional methods such as dissolving the free uracil in an aqueous or nonaqueous solution of at least an equimolar amount of a base or basic salt containing the desired cation. For example, a sodium salt can be prepared by dissolving the uracil in water containing an equimolar amount of sodium hydroxide. The salt can then be isolated from the solution by removal of the water. The uracil salts which are not soluble in water can be prepared by treating an aqueous solution of an alkali metal salt of the uracil with an aqueous solution of a water-soluble salt of the metal.

20 The quaternary ammonium salts of the compounds of Formula 1 are prepared by reacting the substituted uracil with an appropriate quaternary ammonium hydroxide. Since these hydroxides are generally available in solution, the reaction is most conveniently carried out in the same solvent. If the solvent-free salt is desired, it can be easily prepared by removing the solvent.

25 Alternatively, the quaternary ammonium salts of the uracils can be prepared in a dry inert solvent such as toluene or xylene. The sodium salt of the uracil is first prepared and appropriate quaternary ammonium halide is then added with stirring and, if necessary, mild heating. The sodium halide which forms is removed by filtration, leaving the quaternary ammonium salt of the uracil in solution. If desired, the solvent-free salt can be prepared by removing the solvent, preferably in vacuo.

30 The nitrogenous base-uracil addition compounds of Formula 2 are prepared by mixing an appropriate uracil with a 4 to 20-fold weight excess of nitrogenous base. The mixture is heated gently until a clear solution forms.

35 The addition compounds thus formed are stable in the presence of excess amine and can be diluted with suitable solvents for herbicidal applications.

40 The complexes of Formula 3 are formed by co-melting a uracil and a phenol in a 1:2 to 2:1 (uracil:phenol) ratio. They can also be formed by co-dissolving the reactants, in the same ratio, in a nonpolar solvent such as nitromethane or a mixture of nitromethane and cyclohexane.

45 When the phenol complexes are formed by co-melting, it is not necessary to purify them further for herbicidal uses. If solvents are used in their preparation, they can be isolated by filtration or evaporation of the solvent.

50 The complexes so obtained are also suitable for herbicidal use without further purification.

HERBICIDAL COMPOSITIONS

55 The uracil compounds described in Formulae 1 through 4 can be prepared for use by incorporating them with adjuvants.

60 The amount of herbicide in such preparations can vary over a wide range according to need. Generally speak-

ing, they will contain from about 0.5% to 95%, by weight of a uracil.

Powder and dust preparations can be made by mixing uracils of the invention with finely-divided solids such as talcs, natural clays, pyrophyllite, diatomaceous earth; flours such as walnut shell, wheat, redwood, soya bean and cotton seed; or inorganic substances such as magnesium carbonate, calcium carbonate, calcium phosphate, sulfur and lime. These preparations are made by thoroughly blending the active ingredient and the solid. The particles in such preparations should be less than 50 microns in average diameter, preferably about 20 microns.

Water-soluble powders can be prepared by blending a suitable uracil with such water-soluble alkaline powders as silicates, carbonates, phosphates or hydroxides, and optionally with water-soluble diluents such as urea or dextrose.

Granules and pellets can be made by mixing a finely-divided uracil with a suitable clay such as kaolinite, montmorillonite or attapulgite, moistening this mixture with from 15 to 20% by weight of water, and then extruding the mass through a suitable die under pressure. The extrusions are cut into pre-determined lengths and then dried. These pellets can be granulated if desired.

Granules or pellets can also be prepared by spraying a suspension or solution of a uracil onto the surface of a preformed granule of clay, vermiculite or other suitable granular material. If the uracil is in solution, it will penetrate into the pores of the granules and so will adhere without the aid of a binding agent. When the active material is insoluble in the liquid and is carried as a suspension, it is preferable that a binding agent such as goulac, dextrin, swollen starch, glue or polyvinyl alcohol be added. In either case, the granule is then dried and ready for use.

The uracils can also be prepared in liquids. Water and aliphatic and aromatic hydrocarbons, especially those derived from petroleum and having boiling points of from 125° C. to 400° C. are preferred. Hydrocarbons having lower boiling points should not be used because of their undesirable volatilization characteristics and inflammability. These liquid preparations are made by dissolving the active in the liquid, or, if the active is insoluble in the liquid, by milling the components in a mill such as a pebble mill until the particles have average diameters of from 1 to 50 microns, preferably 5 to 20 microns.

The herbicidal preparations, whatever physical form they take, can also contain a surface-active agent. The surfactant renders the preparations readily dispersible in liquids and improves their action on waxy leaves and the like. For general application, surface-active agents are used in the preparations at concentrations of from about 1 to 10% by weight. Levels of from 0.5 to 6 parts of surfactant for each part of uracil, however, give unusual and unexpected results. Preparations having these higher levels of surfactants show greater herbicidal effectiveness than can be expected from a consideration of activity of the components used separately.

The term "surface-active agent" is intended to include wetting agents, dispersing agents, suspending agents and emulsifying agents. Surface-active agents suitable for use are set forth in "Detergents and Emulsifiers . . . up-to-date," 1962, John W. McCutcheon, Inc., Morristown, New Jersey. Other surface-active agents which can be used in these preparations are listed in U.S. Patents 2,139,276; 2,412,510; 2,426,417; 2,655,447; and Bulletin E-607 of the Bureau of Entomology and Plant Quarantine of the U.S. Department of Agriculture.

The preparations can also contain adhesives, corrosion inhibitors, antifoam agents, dyes and pigments, anticaking agents, and hard water stabilizers.

The salts of the compounds of Formula 1 are especially advantageous for use as herbicides because many are

soluble in water and can be applied as aqueous solutions.

With respect to the nitrogenous base-addition compounds of Formula 2, it has been found that preparation with polar low-molecular weight amines, such as ethanolamines, propanolamines and butanolamines gives addition compounds which are extendable in water when the amine is present in excess. Other amines, such as piperidine and octanolamines give addition compounds (in an excess of the amine) which are soluble in both water and hydrocarbon solvents. At the other end of the scale, amines such as dodecylamines, oleyldiamines and tallowamines give addition compounds (in the presence of an excess of the amine) with high hydrocarbon solubility.

Thus, it is apparent that by properly selecting an amine and forming an addition compound with it, the compounds of Formula 2 can be formulated as aqueous solutions or as oil-emulsifiable or oil-extendable formulations. In this way, the nitrogenous base-addition compounds give formulation and application advantages, while still maintaining the desirable herbicidal characteristics of the parent uracils.

FORMULATION WITH OTHER HERBICIDES

The herbicidal compositions of this invention can be formulated to contain two or more of the uracils. They can also be formulated to contain other known herbicides in addition to the uracils to give compositions which have advantages over the individual components.

Among the known herbicides which can be combined with the uracils are:

SUBSTITUTED UREAS

- 3-(3,4-dichlorophenyl)-1,1-dimethylurea
- 3-(4-chlorophenyl)-1,1-dimethylurea
- 3-phenyl-1,1-dimethylurea
- 3-(3,4-dichlorophenyl)-3-methoxy-1,1-dimethylurea
- 3-(4-chlorophenyl)-3-methoxy-1,1-dimethylurea
- 3-(3,4-dichlorophenyl)-1-n-butyl-1-methylurea
- 3-(3,4-dichlorophenyl)-1-methoxy-1-methylurea
- 3-(4-chlorophenyl)-1-methoxy-1-methylurea
- 3-(3,4-dichlorophenyl)-1,1,3-trimethylurea
- 3-(3,4-dichlorophenyl)-1,1-diethylurea
- 3-(p-chlorophenoxyphenyl)-1,1-dimethylurea

These ureas can be mixed with the uracils in proportions of from 1:4 to 4:1, respectively, the preferred ratio being 1:2 to 2:1.

SUBSTITUTED TRIAZINES

- 50 2-chloro-4,6-bis(ethylamino)-s-triazine
- 2-chloro-4-ethylamino-6-isopropylamino-s-triazine
- 2-chloro-4,6-bis(methoxypropylamino)-s-triazine
- 2-methoxy-4,6-bis(isopropylamino)-s-triazine
- 2-ethylamino-4-(2-methoxyethylamine)-6-chloro-s-triazine
- 2-isopropylamino-4-methoxyethylamino-6-methylmercapto-s-triazine
- 2-methylmercapto-4,6-bis(isopropylamino)-s-triazine
- 2-methylmercapto-4,6-bis(ethylamino)-s-triazine
- 60 2-methylmercapto-4-ethylamino-6-isopropylamino-s-triazine
- 2-methoxy-4,6-bis(ethylamino)-s-triazine
- 2-methoxy-4-ethylamino-6-isopropylamino-s-triazine
- 2-chloro-4,6-bis(isopropylamino)-s-triazine

These triazines can be mixed with the uracils in proportions of from 1:4 to 4:1, respectively, the preferred ratio being 1:2 to 2:1.

PHENOLS

- 70 Dinitro-o-sec-butylphenol and its salts
- Pentachlorophenol and its salts

These phenols can be mixed with the uracils in the proportions of 1:10 to 20:1, respectively, the preferred ratio being 1:5 to 5:1.

CARBOXYLIC ACIDS AND DERIVATIVES

The following carboxylic acids and derivatives can be mixed with the uracils in the listed respective proportions:

- A. 2,3,6-trichlorobenzoic acid and its salts
 2,3,5,6-tetrachlorobenzoic acid and its salts
 2-methoxy-3,5,6-trichlorobenzoic acid and its salts
 2-methoxy-3,6-dichlorobenzoic acid and its salts
 3-amino-2,5-dichlorobenzoic acid and its salts
 3-nitro-2,5-dichlorobenzoic acid and its salts
 2-methyl-3,6-dichlorobenzoic acid and its salts
 2,3-dichloro-6-methylbenzoic acid and its salts
 2,4-dichlorophenoxyacetic acid and its salts and esters
 2,4,5-trichlorophenoxyacetic acid and its salts and esters
 (2-methyl-4-chlorophenoxy)acetic acid and its salts and esters
 2-(2,4,5-trichlorophenoxy)propionic acid and its salts and esters
 2-(2,4,5-trichlorophenoxy)ethyl-2,2-dichloropropionate
 4-(2,4-dichlorophenoxy)butyric acid and its salts and esters
 4-(2-methyl-4-chlorophenoxy)butyric acid and its salts and esters
 2,3,6-trichlorobenzylxopropanol

Mixed in a 1:20 to 8:1 ratio, preferably a 1:4 to 4:1 ratio.

- B. 2,6-dichlorobenzonitrile

Mixed in a 1:4 to 4:1 ratio, preferably a 1:3 to 3:1 ratio.

- C. Trichloroacetic acid and its salts

Mixed in a 1:4 to 25:1 ratio, preferably a 1:2 to 10:1 ratio.

- D. 2,2-dichloropropionic acid and its salts

Mixed in a 1:4 to 10:1 ratio preferably a 1:2 to 5:1 ratio.

- E. N,N-di(n-propyl)thiolcarbamic acid, ethyl ester
 N,N-di(n-propyl)thiolcarbamic acid, n-propyl ester
 N-ethyl-N-(n-butyl)thiolcarbamic acid, ethyl ester
 N-ethyl-N-(n-butyl)thiolcarbamic acid, n-propyl ester

Mixed in a 1:2 to 24:1 ratio, preferably a 1:1 to 12:1 ratio.

- F. N-phenylcarbamic acid, isopropyl ester

N-(m-chlorophenyl)carbamic acid, isopropyl ester
 N-(m-chlorophenyl)carbamic acid, 4-chloro-2-butyinyl ester

Mixed in a 1:2 to 24:1 ratio, preferably a 1:2 to 12:1 ratio.

- G. 2,3,6-trichlorophenylacetic acid and its salts

Mixed in a 1:20 to 8:1 ratio, preferably a 1:4 to 4:1 ratio.

- H. 2-chloro-N,N-diallylacetamide

Maleic hydrazide

Mixed in a 1:2 to 10:1 ratio, preferably a 1:1 to 5:1 ratio.

INORGANIC AND MIXED INORGANIC-ORGANIC SALTS

The following salts can be mixed with the uracils in the listed proportions:

- A. Calcium propylarsonate
 Disodium monomethylarsonate
 Octyl-dodecylammoniummethylarsonate
 Dimethylarsinic acid

Mixed in a 1:4 to 4:1 ratio, preferably a 1:2 to 2:1 ratio.

B. Sodium arsenite

Mixed in a 1:10 to 40:1 ratio, preferably a 1:5 to 25:1 ratio.

- C. Lead arsenate
 Calcium arsenate

Mixed in a 150:1 to 600:1 ratio, preferably a 100:1 to 400:1 ratio.

- D. Sodium tetraborate hydrated, granulated
 Sodium metaborate
 Sodium pentaborate
 Polychloroborate
 Unrefined borate ore, such as borascu

15 Mixed in a 3:1 to 1500:1 ratio, preferably a 6:1 to 1000:1 ratio.

E. Ammonium thiocyanate

Mixed in a 1:10 to 20:1 ratio, preferably a 1:5 to 5:1 ratio.

F. Sodium chlorate

Mixed in a 1:1 to 40:1 ratio, preferably a 2:1 to 20:1 ratio.

G. Ammonium sulfamate

Mixed in a 1:1 to 100:1 ratio, preferably a 1:1 to 50:1 ratio.

OTHER ORGANIC HERBICIDES

30 The following herbicides can be mixed with the uracils in the listed respective proportions:

- A. 5,6-dihydro-(4A,6A) - dipyrido- (1,2-A,2',1'-C) pyrazinium dibromide

Mixed in a 1:20 to 16:1 ratio, preferably a 1:5 to 5:1 ratio.

- B. 3-amino-1,2,4-triazole

Mixed in a 1:20 to 20:1 ratio, preferably a 1:5 to 5:1 ratio.

- C. 3,6-endoxohexahydrophthalic acid

45 Mixed in a 1:4 to 20:1 ratio, preferably a 1:2 to 10:1 ratio.

D. Diphenylacetonitrile

- 50 N,N-dimethyl- α , α -diphenylacetamide
 N,N-di(n-propyl)-2,6-dinitro-4-trifluoromethyl-aniline
 N,N-di-(n-propyl)-2,6-dinitro-4-methylaniline

55 Mixed in a 1:10 to 30:1 ratio, preferably a 1:5 to 20:1 ratio.

- E. O-(2,4-dichlorophenyl)-O-methyl-isopropyl-phosphoramidothioate

60 2,3,5,6-tetrachloroterephthalic acid, dimethyl ester

Mixed in a 1:4 to 20:1 ratio, preferably a 1:3 to 15:1 ratio.

- F. 2,4-dichloro-4'-nitrodiphenyl ether

Mixed in a 1:10 to 30:1 ratio, preferably a 1:5 to 20:1 ratio.

OTHER SUBSTITUTED URACILS

The uracils of this invention can be mixed with other substituted uracils, in the respective proportions listed below. Methods for the preparation of the listed uracils can be found in copending applications Serial Nos. 159,746, filed December 15, 1961; 167,434, filed February 75

159,746, filed December 15, 1961; 167,434, filed February

1, 1962; 89,673, filed February 16, 1961; and 89,672, filed February 16, 1961.

3-isopropyl-5-bromo-6-methyluracil
3-isopropyl-5-chloro-6-methyluracil
3-sec.-butyl-5-bromo-6-methyluracil
3-sec.-butyl-5-chloro-6-methyluracil
3-cyclohexyl-5-bromo-6-methyluracil
3-cyclohexyl-5-chloro-6-methyluracil
3-tert.-butyl-5-bromo-6-methyluracil
3-tert.-butyl-5-chloro-6-methyluracil

Mixed in a 1:6 to 6:1 ratio, preferably a 1:4 to 4:1 ratio.

3-cyclohexyl-6-methyluracil
3-cyclohexyl-6-ethyluracil
3-cyclohexyl-6-sec.-butyluracil
3-cyclohexyl-6-propyluracil
3-cyclopentyl-6-methyluracil
3-cyclohexyluracil

Mixed in a 1:6 to 6:1 ratio, preferably a 1:4 to 4:1 ratio.

3-isopropyl-5-bromouracil
3-sec.-butyl-5-bromouracil
3-sec.-butyl-5-chlorouracil
3-cyclohexyl-5-bromouracil
3-cyclohexyl-5-chlorouracil

Mixed in a 1:4 to 4:1 ratio, preferably a 1:2 to 2:1 ratio.

3-isopropyl-1-trichloromethylthio-5-bromo-6-methyluracil
3-cyclohexyl-1-trichloromethylthio-5-bromo-6-methyluracil

3-sec.-butyl-1-acetyl-5-bromo-6-methyluracil
3-isopropyl-1-acetyl-5-bromo-6-methyluracil
3-isopropyl-1-trichloromethylthio-5-chloro-6-methyluracil

Mixed in a 1:4 to 4:1 ratio, preferably a 1:2 to 2:1 ratio.

EXAMPLES

This invention will be better understood by referring to the following illustrative examples:

PREPARATION OF COMPOUNDS

Example 1.—Preparation of 3-isopropyl-5,6-trimethyleneuracil

A mixture of 404 parts by weight of isopropylurea, 686 parts by weight of ethyl 2-cyclopentanone-1-carboxylate, 40 parts by weight of phosphoric acid, 1000 parts by weight of dioxane, and 879 parts by weight of benzene is stirred at reflux for 4 hours. During this time, the water given off by the reaction is trapped out. The solvent is stripped at reduced pressure and a portion of the resulting solid is recrystallized from cyclohexane to give 2-(3-isopropylurido)-1-cyclopentene carboxylic acid, ethyl ester.

The remaining unrecrystallized solid is dissolved in 2360 parts by weight of absolute alcohol containing 248 parts by weight of sodium methoxide, and is refluxed for 10 minutes. The solvent is stripped at reduced pressure and the residue dissolved in water, cooled, and acidified. The solid is filtered off, dried, and recrystallized from ethanol to give the desired 3-isopropyl-5,6-trimethyleneuracil, melting at 222–223.5° C.

Example 2.—Preparation of 3-cyclohexyl-5,6-trimethyleneuracil

A mixture of 343 parts by weight of ethyl 2-cyclopentanone-1-carboxylate, 284 parts by weight of cyclohexylurea, 10 parts by weight of p-toluene sulfonic acid, and 1750 parts by weight of xylene is stirred at reflux for 6 hours. During this time the water given off by the reaction is trapped out. The solvent is stripped from the resulting solution at reduced pressure. The residue is then dissolved in 793 parts by weight of absolute ethyl alcohol.

To this solution is added a mixture of 120 parts by weight of sodium methoxide in 400 parts by weight of absolute ethyl alcohol. The mixture is then refluxed for 10 minutes. The solvent is stripped from this mixture and the resulting solid is dissolved in 3000 parts by weight of water.

This solution is cooled, acidified with excess hydrochloric acid and the solid is filtered off. Recrystallization of this solid from dimethylformamide gives light gray crystals of the desired uracil, melting at 310–313° C.

Example 3.—Preparation of 3-allyl-5,6-trimethyleneuracil

To a warm stirred slurry of 300 parts by weight of allylurea and 1758 parts by weight of benzene is added a solution of 40 parts by weight of 100% phosphoric acid in 468 parts by weight of ethyl 2-cyclopentanone-1-carboxylate. The slurry is refluxed for 16 hours during which the water given off by the reaction is trapped out.

The resulting solution is decanted and concentrated to an oil.

A solution of 180 parts by weight of sodium methoxide in 1400 parts by weight of ethyl alcohol is added to this oil and the mixture is refluxed for ten minutes. The solution is then concentrated to dryness and the residue dissolved in 2000 parts by weight of water.

The aqueous basic solution is extracted free of neutral impurities with 1500 parts by weight of ether. It is then cooled and acidified to a pH of 2 with hydrochloric acid. Solid, white 3-allyl-5,6-trimethyleneuracil, melting at 163.5–166° C., precipitates, which is filtered and dried.

The compounds listed in the following table can be prepared according to the procedures of Examples 1, 2 or 3 by substituting equivalent amounts of the listed ureas, thioureas and alkyl-2-cycloalkanone-1-carboxylates for those used in the examples:

Substituted urea	Parts by weight	Ester of the cycloalkanone carboxylate	Parts by weight	Substituted uracil product
Methyl-2-thiourea.....	90	Ethyl 2-cyclopentanone-1-carboxylate.....	162	3-methyl-5,6-trimethylene-2-thiouacil.
n-Butylurea.....	116	do.....	162	3-n-butyl-5,6-trimethyleneuracil.
n-Hexylurea.....	144	do.....	162	3-n-hexyl-5,6-trimethyleneuracil.
Isooctylurea.....	172	do.....	162	3-isooctyl-5,6-trimethyleneuracil.
α-Naphthylurea.....	204	do.....	162	3-(α-naphthyl)-5,6-trimethyleneuracil.
Tert.-butylurea.....	110	Ethyl 2-cyclohexanone-1-carboxylate.....	187	3-tert.-butyl-5,6-tetramethyleneuracil.
n-Octylurea.....	172	do.....	187	3-n-octyl-5,6-tetramethyleneuracil.
Cyclooctylurea.....	170	Methyl 2-cyclopentanone-1-carboxylate.....	156	3-cyclooctyl-5,6-trimethyleneuracil.
Cyclopentenylurea.....	126	do.....	156	3-cyclopentenyl-5,6-trimethyleneuracil.
Fenethylurea.....	216	do.....	156	3-fenethyl-5,6-trimethyleneuracil.
Cyclopentylurea.....	128	Ethyl 2-cyclohexanone-1-carboxylate.....	187	3-cyclopentyl-5,6-tetramethyleneuracil.
1-(4-methoxycyclohexylurea).....	172	do.....	187	3-(4-methoxycyclohexyl)-5,6-tetramethyleneuracil.
1-(3,4-dichlorocyclohexylurea).....	211	Ethyl 2-cyclopentanone-1-carboxylate.....	187	3-(3,4-dichlorocyclohexyl)-5,6-trimethyleneuracil.

Table—Continued

Substituted urea	Parts by weight	Ester of the cycloalkanone carboxylate	Parts by weight	Substituted uracil product
Cyclooctenylurea	168	Methyl 2-cyclohexanone-1-carboxylate	162	3-cyclooctenyl-5,6-tetramethylene-uracil
Carvacrylurea	191	Methyl 2-cycloheptanone-1-carboxylate	187	3-carvacryl-5,6-pentamethylene-uracil
Isopropylurea	102	do	162	3-isopropyl-5,6-pentamethylene-uracil
n-Amylurea	130	Ethyl 2-cycloheptanone-1-carboxylate	202	3-n-amyl-5,6-pentamethylene-uracil
Bromonorbornylurea	231	do	202	3-bromonorbornyl-5,6-pentamethylene-uracil
Cycloheptenylurea	156	do	202	3-cycloheptenyl-5,6-pentamethylene-uracil
Norbornylurea	152	Methyl 2-cyclopentanone-1-carboxylate	156	3-norbornyl-5,6-trimethylene-uracil
Chloronorbornylurea	188.5	do	156	3-chloronorbornyl-5,6-trimethylene-uracil
Bornylurea	216	do	156	3-bornyl-5,6-trimethyleneuracil
1-cyclohexyl-2-thiourea	154	Ethyl 2-cyclopentanone-1-carboxylate	162	3-cyclohexyl-5,6-trimethylene-2-thiourea
Norbornylurea	154	do	162	3-norbornyl-5,6-trimethylene-uracil
3-cyclopropylmethylurea	115	Ethyl 2-cycloheptanone-1-carboxylate	202	3-cyclopropylmethyl-5,6-pentamethyleneuracil
2-methoxyethylurea	118	do	202	3-(2-methoxyethyl)-5,6-pentamethyleneuracil
Allylurea	100	Ethyl 2-cyclohexanone-1-carboxylate	187	3-allyl-5,6-tetramethyleneuracil
Decenylurea	200	Ethyl 2-cycloheptanone-1-carboxylate	202	3-decetyl-5,6-pentamethylene-uracil
1-allyl-2-thiourea	100	Ethyl 2-cyclopentanone-1-carboxylate	162	3-allyl-5,6-trimethylene-2-thiourea
Decahydronaphthylurea	196	do	162	3-decahydronaphthyl-5,6-trimethyleneuracil
1-(4-isopropylcyclohexyl)urea	185	do	162	3-(4-isopropylcyclohexyl)-5,6-trimethyleneuracil
1-(1-ethylhexyl)urea	158	do	162	3-(1-ethylhexyl)-5,6-trimethylene-uracil
1-(1,1-dimethylbutyl)urea	144	Ethyl 2-cycloheptanone-1-carboxylate	202	3-(1,1-dimethylbutyl)-5,6-pentamethyleneuracil
1-(3a,4,5,6,7,7a-hexahydro-4,7-methano-5-indenyl)urea	196	Ethyl 2-cyclopentanone-1-carboxylate	162	3-(3a,4,5,6,7,7a-hexahydro-4,7-methano-5-indenyl)-5,6-trimethyleneuracil
1-(3a,4,5,6,7,7a-hexahydro-5-indenyl)-urea	196	Ethyl 2-cyclohexanone-1-carboxylate	187	3-(3a,4,5,6,7,7a-hexahydro-5-indenyl)-5,6-tetramethyleneuracil

Example 4.—Preparation of 3-isopropyl-5,6-trimethyleneuracil, sodium salt

Into a solution of 12 parts by weight of sodium hydroxide and 100 parts by weight of water is added 58 parts by weight of 3-isopropyl-5,6-trimethyleneuracil. This slurry is heated and stirred until the solids are completely dissolved. The sodium salt of the uracil separates on cooling. More of the solid can be forced out of solution by dilution with acetonitrile. The salt is filtered off and dried.

Example 5.—Preparation of 3-isopropyl-5,6-trimethyleneuracil, barium salt

A mixture of 194 parts by weight of 3-isopropyl-5,6-trimethyleneuracil, 600 parts by weight of methyl alcohol, and 54 parts by weight of sodium methoxide is stirred until the components are completely dissolved. To this mixture is added a solution of 224 parts by weight of barium chloride dihydrate in 1000 parts by weight of water. The resulting solution is quickly filtered free of foreign matter. A white solid gradually separates and is filtered off. This is 3-isopropyl-5,6-trimethyleneuracil, barium salt.

The following salts are prepared according to this method by substituting equivalent quantities of an appropriate substituted uracil for the 3-isopropyl-5,6-trimethyleneuracil and the proper di- and polyvalent metal chlorides for barium chloride:

3-cyclohexyl-5,6-trimethyleneuracil, magnesium salt
3-n-butyl-5,6-trimethyleneuracil, calcium salt
3-sec.-butyl-5,6-trimethyleneuracil, iron salt
3-allyl-5,6-trimethyleneuracil, manganous salt

Example 6.—Preparation of 3-cyclohexyl-5,6-trimethyleneuracil, tetrabutylammonium salt

A mixture containing 234 parts of 3-cyclohexyl-5,6-trimethyleneuracil and 865.8 parts of a one-molar solution of tetrabutylammonium hydroxide in methanol is

stirred and heated slightly until solution is complete. The solvent is removed by distillation under reduced pressure. The resulting white solid is essentially pure 3-cyclohexyl-5,6-trimethyleneuracil, tetrabutylammonium salt.

Other quaternary ammonium salts can be similarly prepared by reacting equivalent amounts of an appropriately substituted uracil and a suitable quaternary ammonium hydroxide. The following compounds can be prepared in this fashion:

3-cyclopentenyl-5,6-tetramethyleneuracil, tetramethylammonium salt
3-bornyl-5,6-trimethyleneuracil, trimethylbenzylammonium salt
3-isopropyl-5,6-trimethyleneuracil, trimethyldodecylammonium salt

Example 7.—Preparation of 3-sec.-butyl-5,6-tetramethyleneuracil-piperidine addition compound

A mixture containing one part of 3-sec.-butyl-5,6-tetramethyleneuracil and 4 parts of piperidine is stirred and gently heated until a clear solution is obtained.

By similarly employing equivalent amounts of appropriate uracils and nitrogenous bases in place of the 3-sec.-butyl-5,6-trimethyleneuracil and piperidine, the following uracil-nitrogenous-base-addition products can be prepared:

65 3-sec.-butyl-5,6-pentamethyleneuracil, triethylenediamine addition compound
3-sec.-butyl-5,6-pentamethyleneuracil, ethylenediamine addition compound
70 3-sec.-butyl-5,6-pentamethyleneuracil, octylamine addition compound
3-sec.-butyl-5,6-pentamethyleneuracil, dodecylamine addition compound
3-sec.-butyl-5,6-pentamethyleneuracil, cocoadiamine addition compound

15

3-(2-pentyl)-5,6-tetramethyluracil, piperidine addition compound
3-(3,4-dimethylcyclohexyl)-5,6-trimethyluracil, piperidine addition compound

Example 8.—Preparation of 3-(methylcyclohexyl)-5,6-trimethyluracil-piperidine addition compound

A mixture containing one part of 3-(2-methylcyclohexyl)-5,6-trimethyluracil and 20 parts of piperidine is stirred and gently heated until a clear solution is obtained.

The following can be prepared in the same fashion by substituting equivalent amounts of appropriate uracils and amines for the 3-(2-methylcyclohexyl)-5,6-trimethyluracil and piperidine:

3-sec.-butyl-5,6-trimethyluracil, butylamine addition compound
3-(3-methylcyclohexyl)-5,6-trimethyluracil, piperidine addition compound
3-(3,4-dimethylcyclohexyl)-5,6-trimethyluracil, piperidine addition compound
3-(3-methylcyclohexyl)-5,6-tetramethyluracil, methoxypropylamine addition compound
3-tert. butyl-5,6-tetramethyluracil, hexamethylenediamine addition compound
3-cyclohexyl-5,6-trimethyluracil, piperazine addition compound
3-sec.-butyl-5,6-trimethyluracil, sec.-butylamine addition compound

Example 9.—Preparation of the 1:1 complex of 3-sec.-butyl-5,6-tetramethyluracil with phenol

A mixture of 222 parts of 3-sec.-butyl-5,6-tetramethyluracil and 94 parts of phenol is gradually heated until a clear melt forms. The liquid is stirred to assure complete mixing and is then allowed to cool.

The solid residue is recrystallized twice from cyclohexane. The resulting 3-sec.-butyl-5,6-tetramethyluracil phenol complex melts at 103–104° C.

Example 10.—Preparation of the complex of 3-sec.-butyl-5,6-tetramethyluracil with p-chlorophenol

A mixture of 222 parts of 3-sec.-butyl-5,6-tetramethyluracil and 128 parts of p-chlorophenol is gradually heated until a clear melt forms. The liquid is stirred and allowed to cool. The resulting solid is recrystallized twice from cyclohexane. The resulting white p-chlorophenol complex of 3-sec.-butyl-5,6-tetramethyluracil melts at 91–93° C.

The following complexes can be prepared in a similar fashion by replacing the 3-sec.-butyl-5,6-tetramethyluracil and p-chlorophenol with equivalent amounts of appropriate uracils and phenols:

3-isopropyl-5,6-trimethyluracil, pentachlorophenol complex
3-butyl-5,6-tetramethyluracil, 2,4-dichlorophenol complex
3-(2-hexyl)-5,6-trimethyluracil, p-nitrophenol complex
3-(3-methylcyclohexyl)-5,6-trimethyluracil, p-chlorophenol complex
3-sec.-butyl-5,6-tetramethyluracil, p-methoxyphenol complex

HERBICIDAL COMPOSITIONS

LIQUID FORMULATIONS

Example 11.—Aqueous concentrate

A. An aqueous concentrate is prepared by dissolving the two solid components in water. The product can be readily diluted to use levels and sprayed.

	Percent
3-sec.-amyl-5,6-trimethyluracil, potassium salt	5
Sodium lauryl sulfate	1
Water	94

16

This aqueous concentrate is applied with a pressure-type hand sprayer. Three pounds of active ingredient per acre in 40 gallons of water gives excellent preemergence control of foxtail, watergrass, Johnson grass seedlings in sugar cane.

- 5 B. The following substituted uracils in equivalent amounts can also be formulated as aqueous concentrates according to this procedure:
3-cyclopentenyl-5,6-trimethyluracil, sodium salt
10 3-cyclohexyl-5,6-trimethylene-2-thiouracil, sodium salt
3-sec.-butyl-5,6-tetramethyluracil, sodium salt
3-cyclopentenyl-5,6-tetramethyluracil, sodium salt
15 3-cyclooctyl-5,6-tetramethyluracil, sodium salt
3-cyclohexyl-5,6-tetramethylene-2-thiouracil, sodium salt
3-cycloheptyl-5,6-pentamethylene-2-thiouracil, sodium salt
3-decahydro-2-naphthyl-5,6-trimethyluracil, sodium salt
20 3-bornyl-5,6-trimethyluracil, sodium salt
3-(3-methoxypropyl)-5,6-tetramethyluracil, sodium salt
3-(5-cyanopentyl)-5,6-trimethyluracil, tetramethylammonium salt
25 3-cyclobutylmethyl-5,6-trimethyluracil, sodium salt
3-fenchyl-5,6-trimethyluracil, tetraethylammonium salt
3-norbornyl-5,6-tetramethyluracil, tetrapropylammonium salt
30 3-chloronorbornyl-5,6-tetramethyluracil, tetramethylammonium salt
3-norbornenyl-5,6-trimethyluracil, benzyltrimethylammonium salt
3-cyclohexyl-5,6-trimethyluracil, 2/1 6,7-dihydrodipyrido[1,2-a;2',1'-C]pyrazinium salt
35 3-sec.-butyl-5,6-trimethyluracil, 2/1 6,7-dihydrodipyrido[1,2-a;2',1'-C]pyrazinium salt

These formulations, applied at the rate of 20 pounds (active) in 100 gallons of water to weeds growing around bridge abutments, give excellent control of wild barley, bedstraw, hedge bindweed, wild carrot, cheatgrass, cocklebur, dog fennel and goose grass.

Example 12.—Aqueous dispersion

45 The following ingredients (except the water) are mixed, micropulverized, blended with the water and then sand ground until the particles of active material are less than 5 microns in diameter:

	Percent
50 3-[(m - trifluoromethyl)phenyl] - 5,6-trimethyluracil	30.0
Sodium lignin sulfonate	5.0
Hydrated attapulgite	1.5
Water	63.5

55 This stable suspension, when diluted with water and when applied at the rate of 25 pounds of active ingredient per acre in 100 gallons of water, gives excellent control of such annual weeds as crab grass, foxtail, wild rye, wild 60 barley, bachelor buttons, and lamb's-quarters growing in a parking lot.

The following substituted uracils can be formulated similarly. When applied in a like fashion, in equivalent amounts, they also give good herbicidal results:

65 3-(m-pyridyl)-5,6-trimethyluracil
3-(3-chloro-4-ethoxyphenyl)-5,6-trimethyluracil
3-(p-amyloxyphenyl)-5,6-trimethyluracil
3-(p-methoxyphenyl)-5,6-trimethyluracil
70 3-(2,5-dichloro-4-nitrophenyl)-5,6-trimethyluracil
3-(m-chlorophenyl)-5,6-trimethyluracil
3-(3,4-dimethylphenyl)-5,6-trimethyluracil
3-[p-(sec.-butyl)phenyl]-5,6-trimethyluracil
3-(3-nitro-4-chlorophenyl)-5,6-trimethyluracil
75 3-cyclopentenyl-5,6-trimethyluracil, iron salt

3-(3a,4,5,6,7,7a-hexahydro-4,7-methano-5-indanyl)-5,6-trimethyluracil, calcium salt
 3-sec.-butyl-5,6-tetramethyluracil, manganous salt
 3-isopropyl-5,6-tetramethyluracil, barium salt
 3-methyl-5,6-pentamethyluracil, magnesium salt

Example 13.—Aqueous suspension

The following ingredients are mixed and pebble-milled or sand-milled until substantially all the particles of the active material are under 5 microns in size. The resulting stable thixotropic suspension does not cake on storage and is readily diluted with water to form a very slow settling suspension which requires no agitation during application.

	Percent
3-isopropyl-5,6-tetramethyluracil	28.0
Sodium lignin sulfonate	15.0
Hydrated attapulgite	2.0
Disodium phosphate	0.8
Sodium pentachlorophenate	0.5
Water	53.7

This suspension, when applied as a directed spray at 2 pounds of active ingredient per acre in 30 gallons of water, gives good pre-emergence control of crab grass, mustard species, lamb's-quarters, and rice grass germinating in sugar cane.

Example 14.—Aqueous solution

	Percent
3-sec.-butyl-5,6-tetramethyluracil	20
Piperidine	80

The components are mixed together at room temperature until a clear solution is formed. This solution is extendable with water.

Twenty pounds (active) of this formulation are mixed with 60 gallons of water in a spray tank. Eight pounds of trimethylnonyl ether of polyethylene glycol are added. Only slight agitation is required for complete mixing.

The sixty gallons are sprayed on an area of one acre along roadsides. Excellent kill and residual control of such species as wild oats, cheatgrass, annual bluegrass, crab grass, foxtails, ryegrass, filaree, wild mustard, and beggar tick is obtained.

The following compounds can be substituted for 3-sec.-butyl-5,6-tetramethyluracil-piperidine addition compound, in herbicidally equivalent amounts, and when used in a like fashion, will give good weed control:

3-isopropyl-5,6-pentamethyluracil, piperidine addition compound	
3-tert.-butyl-5,6-tetramethyluracil, piperidine addition compound	
3-tert.-butyl-5,6-pentamethyluracil, ethylenediamine addition compound	
3-n-butyl-5,6-pentamethyluracil, piperidine addition compound	
3-sec.-butyl-5,6-tetramethyluracil, hexamethylenediamine addition compound	
3-sec.-butyl-5,6-pentamethyluracil, sec.-butylamine addition compound	
3-sec.-butyl-5,6-pentamethyluracil, cyclohexylamine addition compound	
3-sec.-butyl-5,6-tetramethyluracil, piperazine addition compound	

Example 15.—Aqueous dispersion

	Percent
3-cyclohexyl-5,6-trimethyluracil	22.50
3-cyclohexyl-5-bromo-6-methyluracil	7.50
Sodium lignin sulfonate	15.00
Hydrated attapulgite clay	1.75
Water	52.95-52.65
NaOH (as needed)	0.30-0.60

The mix is wet-milled until all particles are below 10 microns in size. The pH of the slurry is then adjusted to about 8.5.

This formulation gives exceptional control of vegetation around warehouses and industrial sites. It is dispersed in sufficient water to give good coverage of the area to be sprayed. Applied at the rate of 30 pounds of active ingredients per acre, it gives good control of existing weeds and keeps the area weed-free. Good control of such troublesome weeds as crabgrass, fall panicum, mare's tail, goatweed, smartweed, spotted spurge, morning glory, ragweed, pigweed, lamb's-quarters, buttonweed, foxtail, broomsedge, and Russian thistle is obtained.

Example 16.—Emulsifiable oil

An emulsifiable oil is prepared by mixing the components to give a homogeneous solution. This solution can then be emulsified in water for application.

	Percent
3-(3-pentyl)-5,6-tetramethyluracil	20.0
Alkyl aryl polyether alcohol	2.5
Oil soluble petroleum sulfonate	2.5
Methyl isobutyl ketone	75.0

This emulsifiable oil is useful for directed postemergence weed control in cotton at lay-by. When applied at 2 pounds of active ingredient per acre in 30 gallons of water, it gives excellent control of germinating annual weeds such as crab grass, cockleburr, and water grass.

Example 17.—Emulsifiable oil suspension

The following components are mixed together and milled in a roller mill, pebble mill, or sand mill until substantially all the particles of the active component are under 10 microns in size. The resulting suspension may be emulsified in water or diluted further with weed oils for spray application.

	Percent
3-phenyl-5,6-trimethyluracil	25
Blend of polyalcohol carboxylic esters and oil soluble petroleum sulfonates	6
Isophorone	69

This formulation is diluted with 80 gallons of Lion Herbicidal Oil No. 6 and applied at 20 pounds of active ingredient per acre for the control of morning glory, yarrow, ragweed, wild carrot, water grass, witch grass, and crab grass growing along fence rows. Excellent control is obtained.

Similarly formulated and used in equivalent amounts, with excellent results, are 3-cyclohexyl-5,6-trimethyl-2-thiouracil and 3-(2,3-dichloro-3a,4,5,6,7,7a-hexahydro-4,7-methano-5-indanyl)-5,6-trimethyluracil.

Example 18.—Oil suspension

	Percent
3-allyl-5,6-tetramethylene-2-thiouracil	22
Blend of polyalcohol carboxylic esters and oil soluble petroleum sulfonates	7
Xylene	71

These components are blended, micropulverized, and then sand-ground until the particles have a diameter of 10 microns or less.

This formulation, diluted with Lion Herbicidal Oil No. 6 to a final concentration of 15-25 pounds of active ingredient per 100 gallons of oil, gives excellent control of crab grass, cheatgrass, volunteer wheat and oats growing on railroad sidings.

The following substituted uracils can be used in place of 3-allyl-5,6-tetramethylene-2-thiouracil. When used in equivalent amounts and applied in a similar fashion, they will give outstanding weed control:

3-cycloheptenyl-5,6-trimethylene-2-thiouracil	
3-methyl-5,6-tetramethylene-2-thiouracil	
3-isoamyl-5,6-tetramethylene-2-thiouracil	

3-(1-decahydronaphthyl)-5,6-trimethyleneuracil	
3-(3a,4,5,6,7,7a-hexahydro-4,7-methano-5-indenyl)-5,6-trimethyleneuracil	
3-cyclopentenyl-5,6-tetramethylene-2-thiouracil	
3-tert.-butyl-5,6-pentamethylene-2-thiouracil	
3-norbornylmethyl-5,6-trimethylene-2-thiouracil	
3-cyclohexyl-5,6-pentamethylene-2-thiouracil	
3-cyclooctyl-5,6-pentamethylene-2-thiouracil	
3-phenyl-5,6-trimethylene-2-thiouracil	
3-cyclooctyl-5,6-trimethylene-2-thiouracil	

Example 19.—Oil dispersions

	Percent
3-cyclohexyl-5,6-trimethyleneuracil	12.5
3-(3,4-dichlorophenyl)-1,1-dimethylurea	12.5
Paraffinic hydrocarbon (at least 90% unsulfonatable)	72.0
Soya lecithin	3.0

These components are mixed together and then wet-milled until the particles are below 10 microns in size. The resulting oil suspension can be diluted further with oil for application.

This formulation is dispersed in 80 gallons of diesel oil and sprayed, in a blanket treatment, on vegetation and bare areas along railroad ballast. It is sprayed at a rate of 30 pounds of active ingredients per acre. Good control of Bermuda grass, ragweed, goldenrod, smartweed, seedling Johnson grass, spotted spurge, dogbane, and flower-of-an-hour is obtained.

Example 20.—Oil dispersion

	Percent
3-sec-butyl-5,6-trimethyleneuracil	20.0
2-(2,4,5-trichlorophenoxy)propionic acid	5.0
Diesel oil	75.0

These ingredients are mixed and then wet-milled until the particles of uracil are below 10 microns in size.

This formulation is used for the control of a wide variety of woody and herbaceous perennial weeds and grasses along highway rights-of-way. Dispersed in No. 2 fuel oil, it is sprayed at 15-20 pounds per acre of active ingredients on dense growths of weeds and brush on highway shoulders. Honeysuckle, brambles, water grass, goldenrod, ragweed, leafy spurge, seedling sassafras, maples, sweet gum, and poison ivy are controlled.

Example 21.—Oil dispersion

	Percent
3-cyclohexyl-5,6-tetramethyleneuracil	20.0
2,3,6-trichlorobenzoic acid	10.0
Diesel oil	70.0

These components are mixed and then wet-milled until the insoluble particles are under 10 microns in size.

This formulation is dispersed in 100 gallons of herbicidal oil and sprayed along an oil pipeline at the rate of 30 pounds of active ingredients per acre. Excellent control of leafy spurge, bindweed, panic grass, big bluestem, purpletop, poison ivy, quack grass, seedling oaks, maples, sweet gum, ragweed, goldenrod, honeysuckle, and brambles is obtained. The area is kept clear of troublesome weeds for an extended period.

Example 22.—Oil-extendable formulation

	Percent
3-sec.-butyl-5,6-tetramethyleneuracil 1:1 complex with phenol	75.0
Soya lecithin	2.6
Calcined montmorillonite clay (Pikes Peak clay)	22.4

These ingredients are blended and micropulverized until the particles are under 50 microns in diameter and then reblended until homogeneous.

Eight pounds of this formulation are applied in 80 gallons of Lion Herbicidal Oil No. 6 as a foliar spray to annual weeds growing under electric power line towers. Excellent initial kill and residual control of a population

of crab grass, foxtail, wild mustard, lamb's-quarters, cheat-grass, mustard and shepherd's purse is obtained.

The following uracil-phenol complexes can be formulated in a like manner, and when used in herbicidally equivalent amounts, will give excellent results:

3-neopentyl-5,6-tetramethyleneuracil, p-cresol complex	
3-(3-pentyl)-5,6-tetramethyleneuracil, 2,4-dichlorophenol complex	
3-(4-methoxycyclohexyl)-5,6-trimethyleneuracil, p-nitrophenol complex	
3-(2-pentyl)-5,6-trimethyleneuracil, pentachlorophenol complex	
3-tert.-butyl-5,6-pentamethyleneuracil, phenol complex	
3-phenyl-5,6-pentamethyleneuracil, pentachlorophenol complex	
3-(3-chlorophenyl)-5,6-tetramethyleneuracil, p-chlorophenol complex	
3-cyclohexyl-5,6-trimethyleneuracil, 2,4-dichlorophenol complex	
3-isopropyl-5,6-trimethyleneuracil, pentachlorophenol complex	

SOLID FORMULATIONS*Example 23.—Tank mix*

	Percent
3-cyclohexyl-5,6-tetramethyleneuracil	80.00
Alkyl naphthalene sulfonic acid, Na Salt	1.75
Partially desulfonated sodium lignin sulfonate	1.00
Attapulgite clay	17.25

A wettable powder is prepared with these ingredients by blending and micropulverizing them.

Fifteen pounds of this wettable powder are dispersed in 100 gallons of a water solution containing 20 pounds of a formulation of 85% 2,2-dichloropropionic acid, sodium salt. This composition eradicates grasses and other troublesome weeds from warehouse areas. Excellent control of existing Bermuda grass, quack grass, Johnson grass, ragweed, crab grass, panicum species, and knotweed is obtained by an application of this spray mixture at 150 gallons per acre.

Example 24.—Tank mix

A wettable powder is prepared by blending and micropulverizing the following components:

	Percent
3-cyclohexyl-5,6-trimethyleneuracil	80.00
Alkyl naphthalene sulfonic acid, Na salt	1.75
Partially desulfonated sodium lignin sulfonate	2.00
Attapulgite clay	17.25

This wettable powder and an emulsifiable oil containing 6 pounds per gallon of N,N-dipropylthiobacamic acid, ethyl ester are added to a spray tank to form a dilute mixture, in water, of 3/4 to 1 1/4 pounds of uracil formulation and 1/2 gallon of the ester formulation per 100 gallons.

This dilute suspension-emulsion is applied at the volume rate of 100 gallons per acre to spring-seeded alfalfa. Good control of such weeds as checkweed, smartweed, portulaca, penny cress, yellow rocket, shepherd's purse, ragweed, redroot pigweed, crab grass, annual bluegrass, and henbit is obtained.

Example 25.—Tank mix

	Percent
3-sec.-butyl-5,6-trimethyleneuracil	60.0
Mixed polyoxyethylene esters of fatty acids and oil-soluble petroleum sulfonates	5.0
Attapulgite clay	35.0

An oil-dispersible powder of these ingredients is prepared by blending and then grinding them to a particle size of less than 50 microns.

Twenty pounds of this formulation are mixed in 100 gallons of 0.5% pentachlorophenol in diesel oil. The mixture is sprayed uniformly over an acre of weed-infested railroad right-of-way to give superior control

of existing Johnson grass seedlings, big bluestem, cheat grass, fall panicum, smart weed, velvet leaf, ragweed, pigweed, and broomsedge.

Example 26.—Wettable powder

	Percent
3-cyclohexyl-5,6-trimethyleneuracil	80.00
Sodium diethyl sulfosuccinate	1.75
Partially desulfonated sodium lignin sulfonate	1.00
Calcined, non-swelling montmorillonite type clay (Pikes Peak clay)	17.25

A wettable powder is prepared by blending the components and then micropulverizing them until the particles of the active ingredient are substantially all under 50 microns in size, and then reblending to homogeneity.

When applied at 1 pound of active ingredient per acre in 40 gallons of water, this formulation gives excellent pre-emergence control of crab grass, foxtail, cocklebur, lamb's quarters, and burdock in a newly planted field of cotton. One to three pounds of active ingredient per acre gives good weed control in asparagus, sugar cane, and pineapple. One to two pounds per acre gives excellent pre-emergence control annual weeds such as crab grass, foxtail, wild mustard, ryegrass, and velvetleaf in a newly planted field of spinach.

The following uracils can be similarly formulated, and when use in herbicidally equivalent amounts, will give good general weed control:

3-norbornyl-5,6-trimethyleneuracil	30
3-cycloheptyl-5,6-trimethyleneuracil	25
3-cyclooctyl-5,6-trimethyleneuracil	25

Example 27.—Wettable powder

A wettable powder is prepared by blending the following components, micropulverizing them until substantially all the particles are under 50 microns in size, and then reblending:

	Percent
3-sec.-butyl-5,6-trimethyleneuracil	80.00
Low viscosity methylcellulose	0.25
Alkyl naphthalene sulfonic acid, Na salt	1.75
Disodium phosphate (corrosion inhibitor)	0.80
Attapulgite clay	17.20

This formulation is used as a general-purpose weed killer on industrial sites. At 10 to 20 pounds of active ingredient per acre in 100 gallons of water, excellent control of germinating goldenrod, evening primrose, pokeweed, ox-eye daisy, cocklebur, goose grass, crab grass, and love grass is obtained.

A similar wettable powder can be prepared with 3 - (3 - methylcyclohexyl) - 5,6 - trimethyleneuracil. Applied pre-emergence at 2 pounds (active) per acre in 40 gallons of water, excellent control of crab grass, foxtail, water grass, and mustard in a newly planted field of peanuts is obtained.

Example 28.—Wettable powder

The following components are blended, then micropulverized until substantially all the solids are under 50 microns in particle size, then reblended to homogeneity:

	Percent
3-cyclohexyl-5,6-trimethyleneuracil, barium salt	80.0
Sodium lauryl sulfate	0.6
Sodium lignin sulfonate	2.0
Kaolin clay	17.4

This formulation is used in the manner described in Example 27, with good results.

Example 29.—Wettable powder

The following powder is prepared in the same manner as Example 28, but in addition is passed through an air

attrition mill, such as an air-reductionizer, to reduce the particle size to under 10 microns:

	Percent
3-tert.-butyl-5,6-trimethyleneuracil	80.0
Diethyl sodium sulfosuccinate concreted with sodium benzoate (Aerosol OTB)	2.0
Partially desulfonated sodium lignin sulfonate	1.0
Calcined, non-swelling montmorillonite type clay (Pikes Peak clay)	17.0

This composition is used for pre-emergence application in agricultural crops such as sugar cane, asparagus, and safflower. It is dispersed in 40 gallons of water and sprayed with a pressure sprayer. At 0.5 to 2.0 pounds of active ingredient per acre, excellent control of pigweed, lamb's-quarters, purslane, mustard, crab grass, foxtail, and water grass is obtained.

Example 30.—Wettable powder

20 The following are blended, then micropulverized until the particles are below 50 microns in diameter, and reblended:

	Percent
3-bornyl-5,6-trimethyleneuracil	25
Alkynaphthalene sulfonic acid, sodium salt	1
Partially desulfonated sodium lignin sulfonate	1
Attapulgite clay	73

This wettable powder is suspended in water at a concentration of 15-20 pounds of active ingredient per 100 gallons of water. This suspension is sprayed at the rate of 100 gallons per acre for control of crabgrass, water grass and lamb's-quarters growing around telephone poles.

35 Each of the following uracils can be similarly formulated and applied in 60 gallons of herbicidal oil. At rates of 20-30 pounds (active) per acre, they will give good weed control.

3-(α ,2,4-trimethylbenzyl)-5,6-trimethyleneuracil	40
3-p-chlorobenzyl-5,6-tetramethylene-2-thiouracil	45
3- α -phenethyl-5,6-trimethylene-2-thiouracil	45
3-cyano-5,6-trimethyleneuracil	45
3-(p-fluorophenyl)-5,6-trimethyleneuracil	45
3-(3,4-dichlorophenyl)-5,6-trimethyleneuracil	50
3-(4-bromophenyl)-5,6-trimethyleneuracil	50
3-(m-nitrophenyl)-5,6-trimethyleneuracil	50
3-(3-chloro-p-tolyl)-5,6-trimethyleneuracil	50
3-benzyl-5,6-trimethyleneuracil	50
3-(p-methylbenzyl)-5,6-trimethyleneuracil	50
3-phenethyl-5,6-trimethyleneuracil	50
3-(p-methoxybenzyl)-5,6-tetramethyleneuracil	55
3-(p-sec.-butylphenethyl)-5,6-trimethyleneuracil	55
3-p-nitrobenzyl-5,6-trimethyleneuracil	55
3-p-chlorobenzyl-5,6-trimethyleneuracil	55
3-(α ,2,4-trichlorobenzyl)-5,6-pentamethyleneuracil	55
3-cycloheptylene-5,6-pentamethyleneuracil	55
3-cyclooctenyl-5,6-tetramethyleneuracil	60
3-carvacryl-5,6-pentamethyleneuracil	60
3-isopropyl-5,6-pentamethyleneuracil	60
3-n-amyl-5,6-pentamethyleneuracil	60
3-isoctyl-5,6-pentamethyleneuracil	60
3-cyclopentyl-5,6-pentamethyleneuracil	60
3-tetrahydronaphthyl-5,6-trimethyleneuracil	65
3-bromonorbornyl-5,6-pentamethyleneuracil	65
3-cyclopropyl-5,6-trimethyleneuracil	65
3-(2-cyanoethyl)-5,6-trimethyleneuracil	65
3-(3-hydroxypropyl)-5,6-tetramethyleneuracil	65
3-(buten-2-yl)-5,6-trimethyleneuracil	70
3-(propyn-2-yl)-5,6-trimethyleneuracil	70
3-(cyclopentenylmethyl)-5,6-trimethyleneuracil	70
3-(2-methylcyclohexylmethyl)-5,6-trimethyleneuracil	70
3-(4-methoxycyclohexylmethyl)-5,6-tetramethyleneuracil	70
3-(4-methylcyclohexylmethyl)-5,6-trimethyleneuracil	70
3-furfuryl-5,6-tetramethyleneuracil	75

23

Example 31.—Wettable powder

	Percent
3-(norbornenylmethyl)-5,6-trimethyluracil	75.0
Diethylsodium sulfosuccinate	0.5
Ditertiary acetylenic glycol	0.5
Coconut acid ester of sodium isethionate	0.5
Precipitated sodium silico aluminate	23.5

These components are mixed, and micropulverized until the particles are less than 50 microns in diameter.

An application of this formulation at 25 pounds (active) in 80 gallons water controls beggar tick, wild mustard, lamb's-quarters, plantain, velvetleaf, annual bluegrass, Canadian bluegrass, crabgrass, foxtail, and seedling Johnson grass growing around radar installations.

The following compounds can be formulated in a similar fashion. When used in the same way, at equivalent rates, they give good weed control.

3-(1,4,5,6-tetrachloro-7,7-dimethoxybicyclo[2.2.1]hept-5-en-2-ylmethyl)-5,6-trimethyluracil	
3-(α -ethylbicyclo[2.2.2]oct-5-en-2-ylmethyl)-5,6-trimethyluracil	
3-(4-bromobutyl)-5,6-tetramethyluracil	
3-(3-chloro-1-methylpropyl)-5,6-pentamethyluracil	
3-(5,6,7,8-tetrahydronaphthyl)-5,6-trimethyluracil	
3-(n-hexyl)-5,6-tetramethyluracil	
3-isopropyl-5,6-trimethyluracil	

Example 32.—Wettable powder

	Percent
3-cyclohexyl-5,6-trimethyluracil	16.0
3,6-endoxohexahydrophthalic acid	64.0
Polyoxyethylene tall oil acid ester	3.0
Low viscosity polyvinyl alcohol	0.5
Synthetic fine silica	16.5

This wettable powder is prepared by blending the components and then micropulverizing the mixture until the particles are under 50 microns in size.

This formulation is dispersed in water and sprayed pre-emergence at 5 pounds of active ingredients per acre on a planting of red table beets. Excellent control of crab grass, chickweed, annual morning glory, carpetweed, purslane, smartweed, lamb's-quarters, ragweed, black nightshade, giant foxtail, and velvet leaf is obtained. The crop shows no visible injury.

Example 33.—Wettable powder

	Percent
3-sec.-butyl-5,6-trimethyluracil	40.0
3-(4-chlorophenyl)-1,1-dimethylurea	20.0
Alkyl naphthalene sulfonate, Na salt	1.5
Low viscosity methyl cellulose	0.5
Attapulgite clay	38.0

A wettable powder is prepared by blending these components and then micropulverizing the mixture until the particles are below 50 microns in size.

This formulation controls weeds along railroad rights-of-way. Applied in the spring in about 100 gallons of water and at the rate of 25 pounds of active ingredients per acre, the formulation gives good control of annual ryegrass, bromegrass, ragweed, henbit, goldenrod, field daisy, buckhorn, plantain, water grass, and volunteer rye.

Example 34.—Wettable powder

	Percent
3-cyclohexyl-5,6-tetramethyluracil	40.0
2-chloro-4-ethylamino-6-isopropyl-amino-s-triazine	20.0
Diethyl sodium sulfosuccinate concreted 85-15 with sodium benzoate	1.0
Low viscosity methyl cellulose	0.3
Calcined montmorillonite clay	38.7

A wettable powder is prepared by blending these ingredients and then grinding them until the particles are below 50 microns in size.

A tractor-mounted sprayer which sprays four rows at

24

a time is used to apply this formulation to a field of potatoes, before the potatoes emerge. The formulation is used at a rate of 3 pounds of active ingredients per acre. Such weeds as crabgrass, chickweed, smartweed, purslane, giant foxtail, annual morning glory, Johnson grass seedlings, barnyard grass, bedstraw, and henbit are controlled without visible injury to the potatoes. Excellent yields of potatoes are obtained, with minimum cultivation.

Example 35.—Wettable powder

	Percent
1-(3,4-dichlorophenyl)-3,3-dimethylurea	80.00
Low viscosity methyl cellulose	0.25
Alkyl naphthalene sulfonic acid, sodium salt	1.75
Disodium phosphate	0.80
Attapulgite clay	17.20

These ingredients are blended, micropulverized until all particles are below 50 microns in diameter, and then reblended.

(B)

	Percent
3-cyclohexyl-5,6-trimethyluracil	80.00
Alkyl naphthalene sulfonic acid, sodium salt	1.75
Partially desulfonated sodium lignin sulfonate	1.00
Calcined non-swelling montmorillonite clay	17.25

These ingredients are blended, micropulverized until all particles are below 50 microns in diameter, and then reblended.

Nine parts (active) of the uracil formulation are mixed with one part (active) of the urea formulation.

This mixture, applied at 1.25-2 pounds (total active herbicides) per acre in 40 gallons of water to a new planting of sugar beets, gives excellent control of foxtail, crabgrass, barnyard grass, pigweed, lamb's-quarters, ragweed and velvetleaf.

Example 36.—Pellets

	Percent
3-cyclohexyl-5,6-tetramethyluracil	25
Anhydrous sodium sulfate	10
Sodium lignin sulfonate	10
Ca, Mg bentonite	55

These components are blended and micropulverized, then moistened with 18-20% water and extruded through small die holes. The extrusions are cut as formed to give small pellets which are then dried.

These pellets control both annual and perennial weeds along highway guard rails, around bridges, cyclone fences, and highway signs when applied by hand at levels of 15 to 30 pounds of active ingredient per acre.

The following uracils, when formulated in this manner and used at herbicidally equivalent rates, give good weed control:

3-cyclopropyl-5,6-tetramethyluracil	
3-(chloronorbornyl)-5,6-tetramethyluracil	
3-cyclopentyl-5,6-tetramethyluracil	
3-norbornyl-5,6-tetramethyluracil	
3-indenyl-5,6-tetramethyluracil	
3-naphthylmethyl-5,6-trimethyluracil	
3-(p-cumyl)-5,6-trimethyluracil	
3-(3,4,5-trichlorophenyl)-5,6-tetramethyluracil	
3-(4-isopropylcyclohexyl)-5,6-tetramethyluracil	
3-(decahydro-1,4-5,8-dimethanonaphth-2-ylmethyl)-5,6-trimethyluracil	

Example 37.—Pellets

	Percent
3-cyclohexyl-5,6-trimethyluracil	4
3-(p-chlorophenyl)-1,1-dimethylurea	2
Kaolin clay	37
Mississippi sub-bentonite clay	37
Sodium sulfate	10
Sodium lignin sulfonate	10

These ingredients are blended, micropulverized, pug-milled with 17%–20% water, and then extruded through $\frac{3}{32}$ -inch die holes. The extrusions are cut into $\frac{1}{16}$ -inch lengths and dried.

This formulation controls annual grasses and herbaceous broadleaved weeds in asparagus beds. The pellets are distributed evenly over the top of the beds at a rate of 3 pounds of active ingredients per acre just before the cutting season begins and again at the end of the cutting season. Excellent control of crabgrass, black-eyed Susan, beggar-ticks, prickly lettuce, ragweed, barnyard grass, green foxtail, pigweed, and fall panicum is obtained.

Example 38.—Pellets

	Percent
3-isopropyl-5,6-trimethyluracil	3.33
Phenylmethylurea	6.67
California sub-bentonite clay	80.00
Sodium sulfate, anhydrous	10.00

These ingredients are blended, micropulverized, pug-milled with 15%–20% water, and extruded through $\frac{1}{8}$ -inch holes. The extrusions are cut into $\frac{1}{16}$ -inch lengths, dried, and screened.

This formulation is used to control all vegetation in a fire lane. The pellets are distributed from the air in remote areas of the fire lane at the rate of 40 pounds of active ingredients per acre. Excellent control of elm, sweet gum, oaks, maples, brambles, goldenrod, black-eyed Susan, and honeysuckle is obtained.

Example 39.—Pellets

	Percent
3-cyclohexyl-5,6-trimethyluracil	6.67
3-sec.-butyl-5-chloro-6-methyluracil	3.33
Sodium sulfate, anhydrous	10.00
California sub-bentonite clay	80.00

These ingredients are pelletized in the manner of Example 38.

This formulation keeps lumber yards free of weeds. The pellets are distributed in the spring with a seeder at 20 pounds (actives) per acre. The lumber-yard stacking area is kept free of such pernicious weeds as crabgrass, ragweed, pigweed, Russian thistle, fall panicum, goat weed, cheatgrass, and seedling Johnson grass.

Example 40.—Granules

	Percent
3-isopropyl-5,6-trimethyluracil, Na salt	5
8–15 mesh granular, expanded vermiculite	95

This granular composition is prepared by dissolving the active material in water and spraying it upon the granules while they are being tumbled. The granules are then dried.

These granules are applied at 25 pounds of active ingredient per acre to mixed annual and perennial vegetation growing under cyclone fences, around highway markers, along fence rows, and around oil tank installations. Excellent weed control is obtained.

The following compounds can be formulated in a like manner, and when used in herbicidally equivalent amounts, will give good weed control:

3-cyclohexyl-5,6-trimethyluracil, tetramethyl- ammonium salt
3-sec.-butyl-5,6-trimethyluracil, tetrabutyl- ammonium salt
3-tert.-butyl-5,6-trimethyluracil, tetrabutyl- ammonium salt
3-sec.-amyl-5,6-trimethyluracil, sodium salt
3-naphthyl-5,6-trimethyluracil, potassium salt
3-isopropyl-5,6-trimethyluracil, trimethylbenzyl- ammonium salt
3-(oct-7-enyl)-5,6-trimethyluracil, trimethylbenzyl- ammonium salt

3-(α -decahydro-1,4-5,8-dimethanonaphthyl)-5,6-tri- methyleneuracil, sodium salt
3-(5,6,7,8,10,10-hexachloro-1,2,3,4,4a,5,8,8a-octahydro- 1,4,5,8-dimethano-2-naphthyl)-5,6-trimethyleneuracil, tetrapropylammonium salt

Example 41.—Granules

The following composition is prepared by dissolving the active ingredient in water and spraying the solution upon the attapulgite granules while they are being tumbled. The granules are then dried.

	Percent
3-isopropyl-5,6-trimethyleneuracil, sodium salt	4
Granular 8–15 mesh attapulgite clay	96

These granules are applied by hand or by special spreaders at 2.5 pounds of active ingredient per acre for the pre-emergence control of annual weeds in potatoes. They control crabgrass, chickweed, barnyard grass, goose grass, foxtail, velvetleaf, and germinating Johnson grass without visible injury to the crop.

Example 42.—Granules

The following components are blended and micro-pulverized, then moistened with water and granulated. The granules are then dried and screened.

	Percent
3-n-butyl-5,6-trimethyleneuracil	4
Anhydrous sodium sulfate	10
Non-swelling sub-bentonite clay	86

The granules are applied with a granule spreader at 3 pounds of active ingredient per acre for pre-emergence control of annual weeds in asparagus.

Example 43.—Granules

	Percent
3-chloronorbornyl-5,6-pentamethyleneuracil, potassium salt	5
Preformed attapulgite clay granules, +8 to +15 mesh	95

A granular composition is prepared with these components by dissolving the active material in water and spraying it upon the granules while they are being tumbled. The granules are then dried.

These granules are applied at the rate of 20 to 30 pounds of active ingredient per acre to mixed annual and perennial weeds growing in a lumber storage yard. Excellent control of such weed species as crabgrass, foxtails, seedling Johnson grass, quack grass, dandelion, plantain, lambs quarters, and beggar tick is obtained with spring applications.

The following uracil salts can be substituted for the 3-chloronorbornyl-5,6-pentamethyleneuracil, potassium salt. When applied at equivalent rates, good weed control is observed.

3-cyclohexyl-5,6-trimethyleneuracil, potassium salt
3-cyclopentenyl-5,6-tetramethyleneuracil, potassium salt
3-ethoxycarbonylmethyl-5,6-trimethyleneuracil, lithium salt
3-ethyl-5,6-tetramethyleneuracil, lithium salt
3-tert.-butyl-5,6-trimethyleneuracil, potassium salt
3-fenethyl-5,6-trimethylene-2-thiouracil, potassium salt
3-isopropyl-5,6-trimethyleneuracil, potassium salt
3-sec.-butyl-5,6-tetramethyleneuracil, potassium salt
3-(1-ethyl-1-methylbutyl)-5,6-pentamethyleneuracil, potassium salt
3-isoamyl-5,6-tetramethylene-2-thiouracil, potassium salt
3-allyl-5,6-pentamethyleneuracil, potassium salt
3-(2-decyl)-5,6-trimethyleneuracil, lithium salt
3-methyl-5,6-trimethyleneuracil, lithium salt
3-sec.-butyl-5,6-tetramethyleneuracil, lithium salt

Example 44.—Granules

	Percent
3-cyclohexyl-5,6-trimethyleneuracil	16.67
2 - ethylamino - 4 - isopropylamino-6-methylthio-s-triazine	8.33 5
Kaolin clay	72.00
Low viscosity methyl cellulose	3.00

The ingredients are blended and micropulverized, then pug-milled with 15 to 20% water, and moist-granulated. After drying, the granules are screened to 8-30 mesh.

These granules are distributed along the banks of a drainage canal. Applied at 120 pounds of granules per acre, good control of an existing rank growth of canary grass, smartweed, pigweed, and goldenrod is obtained.

Example 45.—Granules

	Percent
3-isopropyl-5,6-trimethyleneuracil	2.00
Polyoxyethylene tall oil acid ester	0.02
Sodium chlorate, 40%—sodium metaborate, 60%	97.98 20

The surfactant and uracil are first mixed and micropulverized, then suspended in water and sprayed on the remaining granular components while they are being tumbled.

These granules are distributed by hand at the rate of about 1.5 pounds per 100 square feet around airport signal lights. Excellent control of Johnson grass, brambles, poison ivy, honeysuckle, pigweed, ragweed, bindweed, Bermuda grass, cheatgrass, and big bluestem is obtained.

Example 46.—Granules

	Percent
3-cyclohexyl-5,6-trimethyleneuracil	1.0
Trichloroacetic acid, sodium salt	3.0
Attapulgite clay, granular 15-30 mesh	96.0 35

The uracil is micropulverized, suspended in a concentrated aqueous solution of the trichloroacetic acid salt, sprayed on attaclay while it is being tumbled, and then dried.

These granules are laid down in a 14-inch band centered on the row in a sugar beet field. They are applied at the rate of 5 pounds of active ingredients per acre. The sugar beets germinate and grow normally, but chickweed, crabgrass, crowfoot, cheatgrass, ragweed, lambs quarters, little bluestem, foxtail, barnyard grass, and hoary cress are controlled.

Example 47.—Water-soluble powder

	Percent
3-(2-methoxyethyl)-5,6-pentamethyleneuracil	25
Sodium silicate	74
Sodium dioctyl sulfosuccinate	1 50

These components are blended and micropulverized. Forty pounds of this formulation are dissolved in 100 gallons of water containing 0.4% of trimethylnonyl ether of polyethylene glycol. Three hundred gallons of this solution per acre are applied to a germinating stand of crabgrass, annual bluegrass, chickweed and wild mustard. Good control of these weeds is obtained.

The embodiments of the invention in which an exclusive property or privilege is claimed are:

1. A method for the control of undesirable vegetation, said method comprising applying to a locus to be protected from such vegetation a herbicidally effective amount of a compound selected from the group consisting of

(a) compounds of the formula

where:

R is selected from the group consisting of alkyl of 1 through 10 carbon atoms, substituted alkyl of 1 through 10 carbon atoms, wherein said substituent is selected from the group consisting of bromine, chlorine, hydroxy, alkoxy, alkoxycarbonyl, dialkylamino, and cyano, aryl of 6 through 14 carbon atoms, substituted aryl of 6 through 14 carbon atoms, wherein said substituent is selected from the group consisting of chlorine, bromine, fluorine, phenyl, alkoxy, alkyl, nitro, trifluoromethyl, 1,2-tetramethylene, and 1,2-trimethylene, aralkyl of 7 through 15 carbon atoms, substituted aralkyl of 7 through 15 carbon atoms, wherein said substituent is selected from the group consisting of chlorine, alkyl, nitro, and alkoxy, tetrahydronaphthylalkyl, alkenyl of 3 through 10 carbon atoms, alkynyl of 3 through 10 carbon atoms, alkenyl of 3 through 10 carbon atoms, substituted cycloalkyl of 3 through 12 carbon atoms wherein said substituent is selected from the group consisting of bromine, chlorine, methoxy, and alkyl, cycloalkenyl of 4 through 12 carbon atoms, substituted cycloalkenyl of 4 through 12 carbon atoms, wherein said substituent is selected from the group consisting of bromine, chlorine, methoxy, and alkyl, cycloalkyl alkyl of 4 through 13 carbon atoms, cycloalkenyl alkyl of 5 through 13 carbon atoms, (substituted cycloalkyl)alkyl of 5 through 14 carbon atoms, wherein said substituent is selected from the group consisting of bromine, chlorine, methoxy, and alkyl, substituted cycloalkenyl)alkyl of 5 through 14 carbon atoms, wherein said substituent is selected from the group consisting of bromine, chlorine, methoxy, and alkyl, and cyano; X is selected from the group consisting of oxygen and sulfur; and n is a number 3 through 5; and (b) the sodium, potassium, lithium, calcium, magnesium, barium, strontium, iron, manganese and quaternary ammonium salts of the compounds of Formula a.

2. The method of claim 1 wherein the herbicidal active compound is 3-cyclohexyl-5,6-trimethyleneuracil.

3. The method of claim 1 wherein the herbicidal active compound is 3-isopropyl-5,6-trimethyleneuracil.

4. The method of claim 1 wherein the herbicidal active compound is 3-sec-butyl-5,6-tetramethyleneuracil.

5. The method of claim 1 wherein the herbicidal active compound is 3-cyclohexyl-5,6-tetramethyleneuracil.

6. The method of claim 1 wherein the herbicidal active compound is 3-isopropyl-5,6-trimethyleneuracil, sodium salt.

7. The method of claim 1 wherein the herbicidal active compound is 3-tert-butyl-5,6-trimethyleneuracil.

8. The method of claim 1 wherein the herbicidal active compound is 3-cyclohexyl-5,6-trimethyleneuracil potassium salt.

9. A method for the control of undesirable vegetation, said method comprising applying to a locus to be protected from such vegetation a herbicidally effective amount of a compound selected from the group consisting of

29

(a) compounds of the formula

where

R is selected from the group consisting of alkyl of 1 through 10 carbon atoms, 10
 substituted alkyl of 1 through 10 carbon atoms, wherein said substituent is selected from the group consisting of bromine, chlorine, hydroxy, alkoxy, alkoxy carbonyl, dialkylamino, and cyano, 15
 aryl of 6 through 14 carbon atoms, substituted aryl of 6 through 14 carbon atoms, wherein said substituent is selected from the group consisting of chlorine, bromine, fluorine, 20 phenyl, alkoxy, alkyl, nitro, trifluoromethyl, 1,2-tetramethylene, and 1,2-trimethylene, aralkyl of 7 through 15 carbon atoms, substituted aralkyl of 7 through 15 carbon atoms, wherein said substituent is selected from the 25 group consisting of chlorine, alkyl, nitro, and alkoxy, tetrahydronaphthylalkyl, alkenyl of 3 through 10 carbon atoms, alkynyl of 3 through 10 carbon atoms, 30 cycloalkyl of 3 through 12 carbon atoms, substituted cycloalkyl of 3 through 12 carbon atoms, wherein said substituent is selected from the group consisting of bromine, chlorine, methoxy, and alkyl, 35 cycloalkenyl of 4 through 12 carbon atoms, substituted cycloalkenyl of 4 through 12 carbon atoms, wherein said substituent is selected from the group consisting of bromine, chlorine, methoxy, and alkyl, 40 cycloalkyl alkyl of 4 through 13 carbon atoms, cycloalkenyl alkyl of 5 through 13 carbon atoms, (substituted cycloalkyl)alkyl of 5 through 14 carbon atoms, wherein said substituent is selected from the group consisting of bromine, chlorine, 45 methoxy, and alkyl, (substituted cycloalkenyl)alkyl of 5 through 14 carbon atoms, wherein said substituent is selected from the group consisting of bromine, chlorine, methoxy, and alkyl, and cyano;

X is selected from the group consisting of oxygen and sulfur; and

n is a number 3 through 5;

30

(b) the sodium, potassium, lithium, calcium, magnesium, barium, strontium, iron, manganese, and quaternary ammonium salts of the compounds of Formula a;

(c) compounds of the formula

where:

R and n are as defined above, and
 NB is a nitrogenous base having an ionization constant $K_b \geq 10^{-9}$ in water; and

(d) compounds of the formula

where

R and n are as defined above,
 Z is selected from the group consisting of hydrogen, chlorine, bromine, nitro, alkyl of 1 through 3 carbon atoms, and —OR₃ (where R₃ is an alkyl of 1 through 3 carbon atoms);
 Y is selected from the group consisting of chlorine and alkyl of 1 through 3 carbon atoms;
 m is a number 1 through 5; and
 p is selected from the group consisting of 1/2, 1 and 2.
